UNITED STATES PATENT OFFICE.

AUSTEN M. CURTIS, OF EAST ORANGE, NEW JERSEY, ASSIGNOR, BY MESNE ASSIGNMENTS, TO WESTERN ELECTRIC COMPANY, INCORPORATED, A CORPORATION OF NEW YORK.

SIGNALING SYSTEM.

Application filed February 14, 1925. Serial No. 9,175.

This invention relates to signaling systems and more especially it has to do with an arrangement whereby an operator who is in the act of receiving a message from a long submarine cable may signal or interrupt the sending of the operator at the distant end of the cable at any time during the transmission of the message.

It is essential in practically all telegraph systems that a receiving operator during the act of receiving a message from a distant station be capable of signaling or interrupting the sending of the operator at the distant station. Such operations are commonly termed "break" or "breaking service" and are usually found necessary in handling telegraphic communications. Where a telegraph circuit is short enough so that the interruption of the circuit of the receiver affects the current at the sending end of the line, or where a long cable is operated duplex, no special means of "breaking-in" are required. Where a long submarine cable is operated simplex, the receiving operator ordinarily cannot interrupt the sending operator. This condition may frequently cause the loss of considerable time.

While there are ways in which electromagnetic signaling devices may be used to enable the sending operator to be interrupted by the receiving operator, these methods of operation are not entirely satisfactory. The outstanding objection to the use of electromagnetic devices connected to the signaling circuit is the large impedance, usually in the form of a choke coil in a leak or shunt circuit to the transmitter, necessary to prevent the normal signaling currents from affecting the electromagnetic devices which operate to communicate the break signal. The frequencies involved in the transmission of signals over long ocean cables do not exceed a few hundred cycles per second and many of the important frequency components are frequently as low as a few cycles per second. The use of such break systems is not commercially practicable with such submarine cables, not only due to the fact that large impedances cannot be conveniently obtained, but also due to the effect of the leak circuit upon the signaling currents. The core of the large impedance coil in the leak circuit introduces hysteresis which tends to disturb the shape of the transmitted sig-

nals or otherwise interfere with satisfactory transmission.

The principal object of the present invention is the indication of a break signal to a distant sending operator in an efficient and reliable manner, especially when the signal components are of low frequency, as in long submarine cable systems.

Another object is the repeating of high speed telegraph signals transmitted over a line or cable of such a nature that artificial balancing lines cannot well be maintained in adjustment.

Other objects will be apparent from the following description and claims.

In carrying out the invention in its preferred embodiment, there is connected to the signaling conductor or cable, the input circuit of an electron discharge device which has associated with it biasing and delayed tuning arrangements which allow it to be operated only by a signal of the proper polarity and of a duration longer than occurs in the normal transmission of signals. An indicating device is accordingly operated to inform an attendant that the distant operator desires to reverse the direction of transmission.

The invention further provides, when this break operation occurs, for the automatic connection and disconnection of the transmitting and receiving mechanisms at the respective stations with the signaling circuit.

Another feature of the invention is a repeater system arranged for repeating signaling impulses between associated line sections provided with means responsive to a break signal for communicating the break signal to the distant operator and for reversing the connections of the repeater to permit the transmission of signaling impulses in the opposite direction.

Heretofore many different forms of repeating systems have been designed for repeating telegraph signaling impulses from one line section to another but in order to permit the transmission of signaling impulses in either direction, the repeater elements must necessarily be balanced to prevent what is commonly termed "singing". The commonest form of this type of repeater is a bridge arrangement designed to allow transmission in one direction and reception in the opposite direction without producing

any appreciable interference in the adjoining circuit. It has also been the consensus of opinion that greater speed may be attained by operating a circuit duplex, that is, the simultaneous transmission of signals in both directions over the same circuit but experience with permalloy loaded cables has proven that at high speeds of transmission even greater speeds may be achieved through simplex operation, at least with the types of balancing artificial lines so far developed. Also to facilitate the operation of the simplex system repeating apparatus is necessary for repeating the signaling impulses between the respective line sections without causing any of the objectionable features produced due to singing. The repeater developed for the system described and claimed herein is capable of being associated with the line sections in a manner to permit the transmission of signals in either direction, which does not require balancing networks (thereby eliminating adjustments) and which is free of the objections usually present in such repeaters. As stated above, it is essential in simplex operated systems to provide some means for communicating a break signal to a distant transmitting operator to permit the reversal of the direction of transmission. According to another feature of the invention, the repeater system does not require frequent adjustments to compensate for changes in line conditions and may have its connections reversed from a terminal station to permit the transmission of signals in either direction, by the transmission of a break signal.

A better understanding of the invention may be had from the following description, taken in conjunction with the accompanying drawings, in which Fig. 1 illustrates one embodiment of the invention, Fig. 2 shows a modification of the arrangement illustrated in Fig. 1, Figs. 3, 4 and 5 when arranged in the manner indicated in Fig. 6 show the break-in system applied to a mid-line repeater.

Referring for the moment to Fig. 1, the specific apparatus of the invention will now be described. Extending between two remotely situated stations, A and B, is a submarine cable which may be a continuously loaded submarine cable 5 preferably of the construction disclosed in patent to O. E. Buckley, 1,586,874, issued June 1, 1926. The cable 5 consists of twin cores for a short distance from each end, one core of which extends through the entire length of the cable and connects the signaling apparatus at the respective stations. The cores extending from each end of the cable terminate in sea earths 7 and 8, respectively.

Located at station A is a transmitter T and a receiver R, which is connected between the sea earth 7 and the signaling core 6,

through an amplifier by means of a switch 9. The switch 9 has three points of connection, one each for connecting the transmitting and receiving mechanisms with the signaling conductor 6, and one for connecting a local source of current therewith. Connected in parallel with the transmitter T and ground is the input circuit of a three-element electron discharge device 10. The electron discharge device 10 has a negative grid battery of the order of 60 volts, in any event higher than the maximum instantaneous voltage impressed on the cable due to the operation of the transmitter T. For this reason no current from the transmitter T can flow through the grid circuit of the device 10 to earth during normal operation of the system. The plate battery which is of the order of 100 volts may be too low to allow any plate current to flow while the transmitter is not in operation or merely low enough to keep the plate current well below the operating current of relay 11. Moreover, the plate voltage is not of sufficient value to cause the flow of space current when negative impulses are being transmitted. However, when positive impulses are transmitted the plate current flows for short intervals during the peaks of the positive impulses. Connected in the output circuit of the electron discharge device is a slow acting relay 11, which controls a dashpot relay 12. The current flowing in the output circuit of the electron discharge device 10 due to the normal operation of the system is usually not sufficient to operate the slow acting relay 11. However, should it operate momentarily the period of operation is insufficient to effect the operation of the dashpot relay 12 controlling through its contacts the operation of a bell or other indicating device 13.

Equipment similar to that just described is also located at the station B and for the sake of brevity further description is not given.

Assume that the station A is transmitting a message to station B, in which event the switches 9 and 14 at the respective stations will be in the positions shown in Fig. 1 of the drawing. If the receiving operator wishes to break or interrupt the sending of the transmitting operator the switch 14 is moved to disconnect the receiver R from the signaling conductor 6 and engage contact 15, which applies a continuous positive voltage to the signaling conductor 6. The voltage thus applied gradually builds up at station A and by neutralizing the grid battery of the device 10 increases the potential of its grid electrode to a point where its normal space current is materially increased. Although the normal space current is still being varied over a wide range due to the operation of the local transmitter T, its

average value is sufficiently high to cause the energization of slow acting relay 11. The slow acting relay 11 now remains closed for an appreciable interval, which permits 5 the operation of the dashpot relay 12 and the closure of its contacts for operating the alarm bell 13 or other indicating device. The operator at station A upon hearing the bell 13 is aware of the fact that the receiving 10 operator at station B desires to reverse the direction of transmission. The switch 9 is then thrown to disconnect the transmitter T and connect the receiver R with the signaling conductor 6. Likewise, at station B, 15 switch 14 is thrown to engage contact 16 for associating the transmitter T with the signaling conductor 6.

Inasmuch as similar apparatus is located at each station, the operator at station A now 20 in the act of receiving messages from station B may interrupt the sending and reverse the direction of transmission in a manner similar to that previously described.

Referring now to Fig. 2, the modification 25 illustrated in this figure will be described. The arrangement shown in this figure is fundamentally the same as that described in connection with Fig. 1, except for the provision of certain devices for effecting the 30 automatic connection and disconnection of the transmitting and receiving mechanisms with the signaling conductor. In place of operating a bell or other signaling device the dashpot relay 12 of Fig. 2 closes at its 35 contacts the circuit of a relay 28. This relay upon being energized establishes through its own contacts and a manually operated key 27, a locking circuit for itself, and also disconnects the transmitter T and connects 40 the receiver R with the signaling conductor 6.

At the station B, certain modifications have been made over the arrangement shown in Fig. 1 for effecting the automatic disconnection and connection of the transmitter T and the receiver R with the signaling conductor 6. This mechanism comprises a 45 spring operated key or switch 20 which is used to commence the train of operations resulting in reversing the direction of signaling. It is moved in the direction of the arrow and first closes contact 21 for completing the energizing circuit of relay 22. This relay locks through its own contact and 50 connects through its front contact a positive voltage from battery 26 to the signaling conductor 6. The operation of the relay 22 also disconnects the receiver R from the signaling conductor 6. Just before the 55 switch 20 reaches its normal position, contact 24 is engaged and closes momentarily a circuit including the winding of relay 25. This relay is thereupon energized and opens the locking circuit of relay 22, which disconnects the source of current 26 from the

signaling conductor 6 and extends this conductor to the armature of relay 25. This relay is also locked up through its own contacts and disconnects the receiver R and connects the transmitter T to the signaling conductor 6. 70

Assume for the purpose of illustration that messages are being transmitted from station A to station B and that the operator at station B desires to interrupt the sending and reverse the direction of transmission. The B operator would then actuate key or switch 20, which is adjusted to consume substantially ten seconds in completing its operation. Contact 21 is first engaged 75 for causing the energization and locking up of relay 22. The locking circuit for this relay may be traced from grounded battery, contacts of key 23, contacts of relay 25, left hand contact and armature of relay 22 and the winding thereof to ground. Relay 22 also connects the source of current 26 with the signaling conductor 6. As described in connection with Fig. 1 the increased positive potential impressed on the signaling conductor 6 due to the connection of a similar source of current therewith causes sufficient space current to flow in the electron discharge device 10 at station A to effect the 80 operation of the slow acting relay 11. Relay 11 is maintained operated for an interval sufficient to permit slow acting relay 12 to close its contacts and cause the energization of relay 28 and the illumination of signal lamp 29. This relay is locked up 85 through its own contacts and disconnects the transmitter T from the signaling conductor 6 and connects the receiver R thereto. The apparatus at station A is now in the proper position for the reception of messages from station B. 90

As the key or switch 20 continues its rotation contact 24 is engaged, whereupon relay 25 is energized for deenergizing relay 22 and connecting the transmitter T to the 95 signaling conductor 6. Messages may now be transmitted from station B to station A. It should be noted in the arrangement just described that the transmitting and receiving mechanisms are automatically connected and disconnected with and from the signaling conductor upon the transmission of a break signal. Keys 23 and 27 at stations B and A respectively are provided for the purpose of opening the locking circuits 100 of relays 25 and 28, thereby restoring the system to normal. 110

The arrangement disclosed in Figs. 3, 4 and 5 will now be described. The apparatus shown in the different figures may be located at stations X, Y and Z, which are connected by means of submarine cables 30 and 66, respectively, the station Y serving as a mid-line repeater for repeating impulses transmitted in both directions. For ex- 115 120 125 130

ample, station X may be designated as New York, station Y as the Azores and station Z as Rome between which points it is desired to transmit messages.

5 The apparatus located at stations X and Z is the same. For the purpose of brevity a detailed description of the apparatus at but one of these stations will be given. It is noted, however, that similar apparatus at 10 these two stations is represented by the same reference character with the prime indice added.

Referring to Fig. 3, there is provided a shaping amplifier A of the type described 15 in detail in my Patent 1,586,970, issued June 1, 1926, combined with a shaping network N of the type described in my Patent 1,586,972, issued June 1, 1926. In transmitting current impulses over a long cable, low 20 frequencies are attenuated much less than the high frequencies and the low frequencies are also retarded in phase more than the higher frequencies. The network N is designed to correct in part at least, the received 25 impulses for phase shift and for attenuation, and at the same time provides a high impedance termination for the signal frequencies.

The input circuit of the first amplifier 30 tube 34 is connected to the secondary winding of the transformer 35, the primary coil of which is included in the first shaping network N. Between the output circuit of the amplifier tube 34 and the input circuit of the amplifier tube 36, there is provided a 35 shaping network so designed as to further compensate for the attenuation of the signaling impulses. Between the output circuit of the amplifier tube 36 and the input circuit of the amplifier tube 37 there is a second network which is designed to reduce 40 high frequency interference. A similar network but having slightly different constants in order to be effective at slightly different 45 frequencies, is connected between the output circuit of the amplifier tube 37 and the input circuit of the amplifier tubes 38 and 39, which have their grid and plate electrodes connected in parallel to provide a materially 50 increased output current. Coupling condensers 40-40 and shunt condensers 41-41 are provided between the different stages as shown.

The change from sending to receiving positions and vice versa is accomplished by 55 means of a relay 50, which is provided with a pair of windings 63 and 64. These windings are energized in accordance with predetermined conditions for associating the 60 transmitter T and the receiver R with the signaling conductor 31 of the cable 30.

When signaling systems in which the received signaling current waves are shaped and amplified before effecting the operation 65 of the receiving apparatus, are used for al-

ternately sending and receiving, it is necessary to provide some means for protecting the receiving apparatus from the flow of excessive currents occurring when the cable is disconnected from the sending apparatus 70

and connected to the receiving apparatus at the end of the signaling period. After the transmitter has been disconnected from the cable and connected to earth there flows from the cable a current which is due to 75 the combined action of the earth current flowing in the cable caused by different potentials of the earth at the respective terminals and the flow to earth of the electric charge absorbed by the cable dielectric during the sending period. This absorbed charge may take several minutes to completely disappear and there still remain the earth currents which are usually capable of producing a potential between the cable and earth far in excess of the normal voltage of the signal for which the system is designed. If the input circuit of the amplifier is connected between the cable and earth and the direct connection between the cable and earth removed there will result a current impulse of many times the voltage of the normal signaling current and containing abnormally high frequency components. Since 80

95 the amplifier and its input circuits are designed so that up to a certain frequency amplification increases in proportion to the frequency, the amplified impulses upon reaching the receiving mechanism may be of sufficient amplitude to seriously damage the apparatus. Furthermore, the high voltages impressed upon the input circuits of the later stages of the amplifier will also materially change the charge of the condensers used for coupling between stages, and by 100 the change of grid voltages thus produced, the amplifier will be rendered inoperative for several minutes or until the normal grid voltages are again established by the charge and discharge of several large condensers 110 through high resistances. In view of the circumstances thus encountered, switching means is provided for protecting the amplifier against excessive current impulses. This 115 particular feature of the invention is accomplished upon the operation of relay 51, which serves to short circuit resistance 52, and the primary section of the auto-transformer between the first and second stages. It might be noted here that the relay 51 120 is normally biased to its open circuit position.

Also located at station X is a suitable key 55 which controls the application of the positive potential to the signaling conductor 31 for the purpose of interrupting the sending of an operator located at station Z and of reversing the direction of transmission. As described in connection with Figs. 1 and 2, a three-element electron discharge device 125 130

60 controls a slow acting relay 61 which in turn controls a dashpot relay 62. The electron discharge device 60 serves the same purpose as described in connection with Figs. 1 and 2 and further detailed information thereof is believed unnecessary.

Coming now to Fig. 4, which illustrates the repeating apparatus located at station Y or the Azores, it is seen that the cables 30 and 66 terminate at this station. As described in connection with the arrangement shown in Fig. 3, a shaping network C and an amplifier D are provided. The shaping network C is connected with the amplifier tube 73 through a shielded transformer 72 in a manner similar to that shown in connection with Fig. 3. Likewise, the amplifier tube 74 is connected with the amplifier tube 73. Although but two stages of amplification have been shown, it is, of course, obvious that further stages may be added without departing from the spirit and scope of this invention. It may even be desirable to employ an amplifier possessing the same characteristics as the one described in connection with Fig. 3, but for the purpose of brevity the amplifier disclosed is believed to be sufficient for the purpose of illustrating this invention.

The input and output circuits of the shaping network C and the amplifier D are arranged to be switched between the signaling conductors of the respective cables 30 and 66, through the operation of a multi-contact relay 77. This relay has two windings and is arranged to be operated upon the completion of predetermined circuits. When transmission is taking place from station X to station Z through the repeater Y, the input circuit of the shaping network C is connected between the signaling conductor 31 of the cable 30 and the sea earth 65 through contacts 75 and 76. Likewise, the output circuit of the amplifier D is connected between the signaling conductor 68 and the sea earth 67 of the cable 66 through contact 78.

In order to permit the reversal of the direction of transmission and the communication of a break signal to the then transmitting operator, suitable mechanism is provided for accomplishing these features without the introduction of any appreciable distortion of the transmitted signals. This mechanism comprises an electron discharge device 81 which has its input circuit operatively connected with the signaling conductor 31 of the cable 30. As described in connection with Figs. 1 and 2, the electron discharge device has a negative grid battery of the order of 60 volts, in any event, higher than the maximum instantaneous voltage impressed on the cable due to the operation of the transmitter. For this reason no current from the transmitter or signaling conductor 31 can flow through the grid circuit of the

tube to earth during the normal transmission of signaling impulses. There is also connected in the plate circuit of the device a battery of approximately 100 volts, which is too low to cause any appreciable plate current to flow during the normal transmission of negative signaling impulses but when positive signals are transmitted the plate current flows over short intervals during the peaks of the positive impulses. There is connected in the output circuit of the electron discharge device 81, a slow acting relay 82, which may momentarily close its contacts under certain conditions, but not for an interval of time sufficient to allow dashpot relay 83 to operate. There is arranged on the armature of the dashpot relay 83 a pair of insulated brushes 88 and 89 which successively engage segments 86 and 87 during its travel. The armature of this relay also effects the closure of contacts 90 when in its extreme uppermost position. When the armature of this relay is in its normal unactuated position or the position shown in the drawing, contacts 84 and 85 are open, the purpose of which will be described hereinafter.

Similarly associated with the signaling conductor 68 of the cable 66 is duplicate apparatus to that just described which responds to a break signal from station Z. It is, of course, to be understood that the respective apparatus serves to reverse the connections of the shaping network C and the amplifier D, as well as the application of the necessary potential for communicating the break signal in accordance with the direction which messages were previously being transmitted.

A better understanding of the invention may be had from the following detailed description of the operation of the system. Assume for the purpose of illustration that signals or messages are being transmitted from station X to station Z through the mid-line repeater Y. Further assume that the multi-contact switch 77 at station Y is in the position shown. When the apparatus is connected to the respective cables in the manner shown signals transmitted from the transmitter T at station X pass over the signaling conductor 31 of the cable 30, extreme left hand back contact of relay 80, contact 75 of multi-contact switch 77, the circuit of the input shaping network C, contact 76 of the multi-contact switch 77 to ground at the sea earth 65. The signals thus received pass through the shielded transformer 72, are amplified and corrected in accordance with the manner previously described and pass over a circuit extending from the output circuit of the amplifier 74, contact 78 of the multi-contact switch 77, contact 94 of relay 91, conductor 68 of the cable 66 to station Z. The impulses upon

being received at station Z pass through the armature and upper contact of relay 50', the circuit of the input shaping network N', primary winding of the transformer 35' to earth at the sea ground 69. The received impulses pass through the respective stages of amplification and are received and recorded on the receiver R.

Assume that while messages are being transmitted in the direction just described that the operator at station Z desires to break the operator at station X and reverse the direction of transmission. Accordingly, key 55' is actuated for performing several sequential operations. Immediately that key 55' is moved from its normal position contact 59' is closed for momentarily grounding the input circuit of the electron discharge device 60', thus preventing its operation and the energization of relays 61' and 62'. When contacts 56' and 57' are closed through the actuation of the key 55', a source of current is applied to the signaling conductor 68 of the cable 66, through the contact 56' and key 55'. The closure of contacts 57' causes the completion of an energizing circuit for relays 50' and 51'. This energizing circuit may be traced from the positive pole of battery, winding 64' of relay 50', contacts 57', lower winding of relay 51' to the negative terminal of the same battery. Relays 50' and 51' are thereupon caused to reverse the position of their armatures, relay 50' disconnecting the input circuit of the shaping network N' and amplifier system A' from the cable and connecting thereto the transmitter T, while relay 51' which is normally biased to the open circuit position short circuits a portion of resistance 52' and the primary winding of the interstage auto-transformer for protecting the amplifier from excessive current impulses resulting from electric charge absorbed by the cable dielectric during the sending period, as is described in my Patent 1,586,971, issued June 1, 1926.

The connection of the current source through contact 56' to conductor 68 of the cable 66 causes sufficient space current to flow through the electron discharge device 81' located at station Y to produce a current flowing in the output circuit thereof over a period to cause the operation of slow acting relay 82'. Relay 82' is thus energized for causing the energization and operation of the dashpot relay 83'. The armature of the dashpot relay 83' is designed to move in the forward direction slowly but upon deenergization restores to its normal position quickly. Immediately that the armature 60 of the relay 83' begins its forward movement, contact 84' is closed which produces no change in the circuit connections as the relay 92 is already in the position to which it would be moved upon the completion of 65 the circuit through the contacts 84' and 85'.

As the armature of the relay 83' continues its travel segment 86' is engaged by brush 89'. Upon the engagement of the brush 89' with the segment 86' an energizing circuit is completed including the right hand winding of relay 92 and the winding of relay 80. This circuit may be traced from the positive pole of battery, right hand winding of relay 92, winding of relay 80, brush 89', segment 86' to the other terminal of the battery. Relays 80 and 92 are energized over the circuit just traced. The former connects through its right hand front contact ground with the grid electrode of the electron discharge device 81, thereby preventing its operation, while at its back contact it disconnects the circuit extending from the conductor 31 of the cable 30 through the contact 75 of the multi-contact switch 77 to the input circuit of the shaping network C and connects at its front contact a source of current for transmitting a positive impulse to station X over the signaling conductor 31, the purpose of which will be described shortly. Relay 92 closes its contact, short circuiting the resistance 93 and the primary winding of the interstage auto-transformer for the purpose of protecting the amplifier as previously described. The armature of the relay 83' continues its travel, disengaging brush 89' with segment 86' and causing the engagement of brush 88' with segment 87'. Upon the engagement of the grounded brush 88' with segment 87', which occurs some little time following the application of the source of current through the operation of relay 80 so that the impulse transmitted has had sufficient time to effect the operation of the apparatus at the station X, the charge on the signaling conductor 31 of the cable 30 is allowed to discharge. By grounding the signaling conductor 31 in this manner the charge absorbed during the transmission of the signaling impulse just referred to is allowed to drain off, thus restoring the cable to a neutral position. Following the disengagement of the brush 88' with segment 87', contacts 90' are actuated by the armature of relay 83'. The closure of these contacts establishes an energizing circuit including the lower winding of the multi-contact relay 77 with a source of current. This relay is thereupon caused to reverse the position of its armature, causing the opening of the previously engaged contacts and the closure of contacts 98, 99 and 100. The engagement of the contacts just enumerated causes the reversal of the connections of the shaping network C and the amplifier D with respect to the conductors 31 of the cable 30 and the conductors 68 of the cable 66, respectively. In other words, the input circuit of the shaping network C is now connected between the conductor 68 and the sea earth 67 of the cable 66, while the output 130

circuit of the amplifier D is associated with the conductor 31 of the cable 30.

In order to clarify the description the sequence of operation occurring at the repeater station Y will now be outlined. The application of the positive potential at station Z causes current to flow in the output circuit of electron discharge device 81'. Relay 82' is energized and dash-pot relay 83' 10 operates through the control of relay 82'. Dash-pot relay 83' first closes contact 84' closing a circuit through the left hand winding of relay 92 but nothing happens as this relay is already in this position. After contact 85' is opened, segment 86' is engaged by brush 89' closing the circuit through the right hand winding of relay 92 which closes its contacts thereby rendering the amplifier ineffective. Brush 89' disengages segment 20 86' and brush 88' engages segment 87' grounding the conductor 31. Finally, after brush 88' has disengaged segment 87', contact 90' is closed energizing relay 77 for reversing the connections of the shaping 25 network C and the amplifier D.

The key 55' at station Z being now released, it being only necessary that it be operated for a short period of time, the source of current applied to the conductor 68 through contact 56' is removed and the cable is discharged by the momentary grounding caused by operation of contacts 58' and 59' so that space current through the tube 81' no longer flows. The relays 82' 30 and 83' are thereupon released, the armature of the latter just before reaching its normal position closes the circuit including contacts 84' and 85' and the armature of this relay. Since contact 84' is at this time closed, an energizing circuit is established, including the left hand winding of relay 92, which is energized for removing the short circuit about the resistance 93. It should be noted that relay 92 is an unbiased polar 40 relay, which remains in the position to which it was last operated.

The impulse applied to the conductor 31 resulting from the operation of relay 80 is impressed on the input circuit of the electron discharge device 60 at station X. Inasmuch as this impulse is applied for an appreciable interval of time, the current in the output circuit is allowed to build up to a sufficient value for effecting the operation of slow acting relay 61. This relay closes at its contacts the energizing circuit for dash-pot relay 62. Dashpot relay 62 in closing its contacts causes the energization of relays 50 and 51. The latter relay short circuits the resistance 52 and the primary coil of the interstage auto-transformer for protecting the amplifier against the electric charge absorbed by the cable during the transmission of the impulses which effect the operation of electron discharge device 60, while

the relay 50 disconnects the transmitter T from the conductor 31 of the cable 30 and connects the input circuit of the shaping network N thereto. As set forth in applicant's copending application, Serial No. 732,900 filed Aug. 19, 1924, it is generally desirable that the short circuit be placed on the amplifier slightly in advance of the transfer from transmitting to receiving. In the circuit arrangement disclosed, the order in which this takes place will depend upon the time constants of relays 50 and 51 and the adjustment of the relay contacts. If these relays are adjusted so that 51 operates in advance of 50, the short-circuiting of the amplifier will take place prior to the application of the receiving network N to the conductor 31. However, the adjustment of these relays may be such that their operation will take place simultaneously if desired. When relay 80 at station Y releases its armature, the source of current applied to the conductor 31 of the cable 30 is disconnected, whereupon the current in the output circuit of electron discharge device 60 diminishes to a point where relay 61 releases its armature, consequently dashpot relay 62 is released, which opens at its contacts the energizing circuit of relays 50 and 51. The former relay is arranged to remain in its actuated position upon the opening of this circuit, but the latter relay is normally biased to the open circuit position or the position shown in the drawing upon the opening of these contacts.

With the operation just described completed, the transmitting and receiving mechanisms at the respective stations are connected and are associated with the respective conductors of the connecting cables in a manner to now permit the transmission of signals from station Z through the repeater Y to station X, which is the reverse direction to that for which the apparatus was previously connected.

The invention has been shown and described as applied to a particular type of system, but it is obvious that various modifications may be made without departing from the spirit and scope of the present invention.

What is claimed is:

1. In a signaling system, transmitting and receiving mechanisms located at the respective stations, a leak circuit associated with said transmitting mechanism, a device substantially free of hysteresis included in said leak circuit and unresponsive to the operation of said transmitting mechanism, and means controlled by the receiving operator for effecting the operation of said device.

2. A signaling system comprising a submarine cable incapable of efficiently transmitting signals involving frequencies of more than a few hundred cycles per second,

- transmitting means at each terminal for transmitting such signals, a circuit in shunt to said transmitting means at each terminal containing means responsive to a break signal from the other terminal, said shunt circuits being of such high impedance and so free from hysteresis that signals are not distorted thereby. 70
3. In a signaling system, transmitting and receiving mechanisms associative with a signaling path extending to a remote station, an electron discharge device responsive to a signal from a distant receiving operator, said device representing to the signaling currents a high impedance at normal signaling frequencies whereby said signaling currents are not appreciably distorted nor reduced in volume, and means controlled by said device for indicating to a sending operator a desire on the part of the receiving operator to reverse the direction of transmission. 75
4. In a signaling system, transmitting and receiving mechanisms associative with a signaling path extending to a remote station, a device responsive to a signal from a distant receiving operator to indicate to a sending operator a desire on the part of the receiving operator to reverse the direction of transmission, said device representing to the signaling currents a high impedance at the frequencies of the normal signaling frequencies whereby said signaling currents are not appreciably distorted nor reduced in volume, and means controlled by said device for reversing the connections of the transmitting and receiving mechanisms with said signaling path. 80
5. In a signaling system, a submarine cable, transmitting and receiving mechanisms associative with said cable, a device associated with said cable responsive to a prolonged positive impulse impressed on the cable, said device being of a character not to appreciably distort or interfere with the shape of the transmitted signals, and having impedance widely different from the cable impedance, and means controlled by said device for communicating a break signal to the transmitting operator. 85
6. In a signaling system, a continuously loaded cable, transmitting and receiving mechanisms associative with said cable, a device associated with said cable, which in response to a prolonged positive impulse impressed on the cable will permit a current to flow in an output circuit of said device, and means operated when current is allowed to flow in the output circuit of said device for an appreciable period of time for communicating a break signal to the transmitting operator. 90
7. In a signaling system, a continuously loaded cable, transmitting and receiving mechanisms associative with said cable, an electron discharge device associated with said cable and responsive to a prolonged positive impulse impressed on the cable, and means controlled by said electron discharge device for automatically reversing the connections of the transmitting and receiving mechanisms with said cable at the transmitting stations. 95
8. In a signaling system, a continuously loaded cable, transmitting and receiving mechanisms associative with said cable, a device associated with said cable and responsive to a prolonged positive impulse impressed on the cable, and slow-acting electromagnetic means controlled by said device for automatically reversing the connections of the transmitting and receiving mechanisms with said cable. 100
9. A signaling system comprising a signaling path, transmitting and receiving mechanisms associative with said signaling path, an amplifier connected to said receiver, means responsive to a break signal transmitted by a receiving operator for reversing the connections of said transmitting and receiving mechanisms with said signaling path, and means controlled by said means for bridging a low impedance circuit across the amplifier to prevent excessive current impulses at the time of connecting the receiving apparatus to the signaling path. 105
10. A signaling system comprising a signaling path, transmitting and receiving mechanisms associative with said signaling path, an amplifier connected to said receiver, means including an electron discharge device responsive to a prolonged positive impulse transmitted by a receiving operator for reversing the connection of the transmitting and receiving mechanisms with said signaling path, and means controlled by said device for bridging a low impedance circuit across the amplifier to prevent excessive current impulses at the time of connecting the receiving apparatus to the signaling path. 110
11. A submarine cable-repeating system for repeating high speed telegraph signals comprising a one way repeating device, switching means for reversing the relationship of the repeating device with respect to the cable, and means unresponsive to normal signaling impulses and controlled from a remote station over a section of the cable for controlling said switching means for changing the direction in which said device will repeat. 115
12. A signaling system comprising a signaling conductor and divided into sections, repeating apparatus intermediate said sections for repeating impulses from one section to another said repeating apparatus including an amplifier, means operated to associate said amplifier with said line sections for transmission of impulses in either direction, means responsive to a special signal for operating said means to reverse the connection. 120

- tions of said amplifier with respect to said sections, and further means operated upon the receipt of a special signal for bridging a low impedance circuit across the amplifier 5 to prevent excessive current impulses at the time the connections of the amplifier are reversed.
13. A signaling system comprising a signaling conductor divided into sections, repeating apparatus intermediate said sections for repeating impulses from one section to another said repeating apparatus including an amplifier, means operated to associate said amplifier with said sections for transmission 10 of impulses in either direction, an electron discharge device responsive to a special signal, and means controlled by said device for operating said means to reverse the connections of said amplifier with respect to the 15 sections of said conductor.
14. A signaling system comprising a signaling conductor divided into sections, repeating apparatus intermediate said sections for repeating impulses from one section to another, said repeating apparatus including an amplifier, means operated to associate said amplifier with said sections for transmission of impulses in either direction, an electron discharge device responsive to a special signal, and a relay controlled by said device for operating said means to reverse the connections to said amplifier with respect to the sections of said conductor. 20
15. A signaling system comprising a signaling conductor divided into sections, repeating apparatus intermediate said sections for repeating impulses from one section to another said repeating apparatus including an amplifier, means operated to associate said amplifier with said sections for transmission of impulses in either direction, an electron discharge device responsive to a special signal, a relay controlled by said device for operating said means to reverse the connections to said amplifier with respect to the sections of said conductor. 25
16. In a signaling system, a conductor divided into sections, receiving and transmitting mechanisms at each of said stations, repeating apparatus intermediate said sections including an amplifier, means for associating said amplifier with said sections for transmission in either direction thereover, an electron discharge device located at the same station as the repeating apparatus responsive to a special signal, means controlled by said special signal for transmitting to the adjoining section a prolonged impulse and for reversing the relationship of said amplifier with respect to said sections, and means at the distant stations responsive to the prolonged impulse for reversing the connections of said transmitting and receiving mechanisms with respect to the signaling conductor. 30
17. In a signaling system a conductor divided into sections, receiving and transmitting mechanisms at each of said stations, repeating apparatus intermediate said sections including an amplifier, means for associating said amplifier with said sections for transmission in either direction thereover, an electron discharge device located at the same station as the repeating apparatus responsive to a special signal, means controlled by said special signal for transmitting to the adjoining line section a prolonged impulse and for reversing the relationship of said amplifier with respect to said sections, means comprising an electron discharge device responsive to the prolonged impulse, and means controlled by said device for disconnecting the transmitting mechanism and connecting the receiving mechanism to the signaling conductor. 35
18. In a signaling system a conductor divided into sections, receiving and transmitting mechanisms at each of said stations, repeating apparatus intermediate said sections including an amplifier, means for associating said amplifier with said sections for transmission in either direction thereover, an electron discharge device located at the same station as the repeating apparatus responsive to a special signal, means controlled by said special signal for transmitting to the adjoining section a prolonged impulse and for reversing the relationship of said amplifier with respect to said sections, and further means also controlled by said device for protecting said receiving equipment against excessive current impulses resulting from the transmission of signaling impulses over said signaling conductor. 40
19. In a signaling system, a submarine cable, a transmitter associated therewith having a direct current resistance that is extremely high compared to that of said cable and a device connected in shunt to said transmitter, said device having an impedance that is extremely high compared to that of the cable for currents of signal frequencies but which will respond to a prolonged positive impulse on said cable to disconnect the transmitter therefrom and connect a receiver thereto. 45
20. A submarine cable repeating system for repeating high speed signals comprising a one-way repeating device and switching means controlled from a remote station over a section of submarine cable for reversing the connections of said cable to said device and consequently changing the direction in which said device will repeat. 50
21. A repeating system for repeating high speed submarine cable telegraph signals 55

comprising a one-way message repeating device, two auxiliary one-way repeating device means for causing, at all times, at least one of said auxiliary devices to be in parallel with said message repeating device, and a switching mechanism for changing the relationship of said message repeating device to the cable, said switching mechanism be-

ing under the control of at least one of said auxiliary devices, said auxiliary devices being of high impedance and substantially reactionless at signal frequencies.¹⁰

In witness wherof, I hereunto subscribe my name this 7th day of February, A. D. 1925.

AUSTEN M. CURTIS.
